(57) **CLAIM**

The ornamental design for a glass cup, as shown and described.

DESCRIPTION

FIG. 1 is a front and top perspective view of a glass cup, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion labeled with numeric 9 in FIG. 1;

FIG. 10 an enlarged view of the portion labeled with numeric 10 in FIG. 1; and,

FIG. 11 is an enlarged view of FIG. 8.

The evenly spaced broken lines in the drawings depict portions of the glass cup that form no part of the claimed design. The dash-dot broken lines shown in FIGS. 1, 9 and 10 are for the purpose of depicting the boundary lines of the enlarged views and form no part of the claimed design.

1 Claim, 11 Drawing Sheets
